UNITED STATES PATENT OFFICE.

JOHN H. MORSE, OF PEORIA, ILLINOIS.

IMPROVEMENT IN WIND-WHEELS.

Specification forming part of Letters Patent No. 59,249, dated October 30, 1866.

To all whom it may concern:

Be it known that I, J. H. MORSE, of the city of Peoria, county of Peoria, State of Illinois, have invented a new and useful Improvement in Windmills; and I do hereby declare the following to be an exact description thereof, reference being had to the accompanying drawings, and to the letters of reference marked thereon.

Figure 1, perspective view of mill; Fig. 2, showing top of mill, looking down from above; Fig. 3, sectional view, showing rack L, segment of cog-wheel M, with steel rod J, clutch K, collar E, lever-rods c c c c c, and their connections; Fig. 4, front view of regulating-fan A, with balance-weight R and pedestals O O.

My improvement consists in a regulating-fan, A, (see Fig. 4,) to be operated upon by the wind, for the purpose of turning the fans of any windmill whose fans may be pivoted or hinged upon its arms.

My manner of building or attaching improvement to windmills is as follows:

Upon the arms of a vertical-armed mill (see Fig. 1) I hinge the fans B B B B B, so that they may be turned from an angle of about forty-five degrees to the wind (the position for running) to "feather-edge." To these fans I fasten iron rods for levers, by which the fans are turned. (See Fig. 2.)

Upon the main shaft D of mill I place a sliding collar, E. (See Fig. 3.) Into the outer rim, I insert eyes f f f f f, through which the lever-rods c c c c c pass.

Passing through the nose G of circular plate T, which forms the bed, and upon which the mill revolves by change of wind, (see Figs. 1 and 2,) and under the bearing I of main shaft D, is a steel rod, J, with clutch K upon its outer end, catching into a groove in collar E.

Attached to rear end of steel rod J is a rack, L, into which the segment of a cog-wheel, M, works. (See Fig. 3.)

Through the center of cog-wheel M passes the shaft N, having its bearings upon pedestals O O. (See Fig. 4.) Upon one end of this shaft N the crank P is formed, to which the balance-weight R is fastened, which acts as a lever to balance the regulating-fan A.

The manner of working the mill is as follows:

The regulating-fan A being held in an up-

right position by means of the balance-weight R, which is heavier than the fan A, and is fastened to the crank P, and may be moved along this crank down to the end (see Fig. 4) if it is required to hold fan A against a stiff breeze, the mill is in position to run.

The cog-wheel M, working in the rack L, will move the collar E backward and forward on the main shaft D, by means of the steel rod J and clutch K, as the fan A is raised or depressed, and thus, by means of lever-rods c c c c c, running through eyes f f f f f in flange of collar E, the fans B B B B B may be turned to receive more or less force from the wind.

If there is more force in the wind than is required to run the mill and do its work, it will depress the regulating-fan A, (see Fig. 3, dotted lines;) then the cog-wheel M, working in rack L, will push forward the steel rod J, and, by means of clutch K, move the collar E along main shaft D. The lever-rods c c c c c running through eyes f f f f f in flange of collar E, the fans B B B B B will be turned at a less angle to the wind and receive less of its power.

In a very strong wind the regulating-fan A will be blown down to a horizontal position, (see dotted lines b, Fig. 3,) which will have the effect to turn the fans B B B B B feather-edge to the wind and stop the mill.

As the wind lessens its power the fan A will rise to an upright position, (see Fig. 1,) and the mill be in position to run. The fan A, with its connections, will be used to stop the mill by attaching a chain or cord to fan A and drawing it down to a horizontal position. (See Fig. 3, dotted lines, b.)

I disclaim the regulating-fan A, having patented it before.

What I do claim as my invention, and desire to secure by Letters Patent, is—

The regulating-fan A, in connection with its balance-weight R, cog-wheel M, rack L, steel rod J, clutch K, collar E, lever-rods c c c c c, attached to fans B B B B B, working in eyes f f f f f in flange of collar E, substantially in the manner and for the purpose specified.

JOHN H. MORSE.
